UNITED STATES PATENT OFFICE.

LORENZO B. SHIVERS, OF ANGLESEA, NEW JERSEY.

IGNITION-TIMER.

No. 911,527.

Specification of Letters Patent.

Patented Feb. 2, 1909.

Application filed June 17, 1908. Serial No. 438,910.

To all whom it may concern:

Be it known that I, LORENZO B. SHIVERS, a citizen of the United States, residing at Anglesea, in the county of Cape May and State 5 of New Jersey, have invented certain new and useful Improvements in Ignition-Timers, of which the following is a specification.

My invention relates to electrical spark ignition timers for internal combustion engines, and particularly to current making and breaking timers in which a rotatable element coacts with a fixed concentric shell provided with contact pieces with which the rotatable element makes and breaks connection.

15 The object of my invention is to provide a timer of this character to be used in jump spark ignition in which there shall be less wear on the internal surface of the fixed element and in which the wear shall be more 20 evenly divided, thus providing for a better contact and preventing the wearing of the internal surface of the timer into ridges.

25 A further object is to provide means for adjusting the length of contact to correspond to a higher or lower rate of speed in the engine.

30 My invention consists broadly in interposing between the rotatable element and the exterior concentric fixed element, a free, rotatable conducting ring actuated by the rotatable element to move against the face of the fixed element and to have a rolling contact therewith.

35 It also consists in the provision of a bushing, projecting beyond the bottom of the timer casing, and acting to hold a layer of oil within the casing.

40 In the drawings, Figure 1, is a plan view of a timer constructed according to my invention, the cover being removed, and Fig. 2, is a diametrical section.

Like reference characters throughout the views designate like parts.

45 A designates a shell or casing of any suitable construction, preferably of metal formed with an annular wall *a* and the projecting tubular bearing *a'* made in one piece therewith.

50 B designates a cover of the usual construction adapted to fit upon and to be attached to the casing by clamping nuts *C* and bolts *C'* in the usual manner. This cover should have an oil-tight engagement with the casing.

55 Lining the interior of the wall *a* and resting on the bottom of the casing or shell *A* is

the insulating ring *D* of fiber or other like material, up through which the bolts *C'* project. Passing through the insulating ring *D* from the exterior of the wall *a* are the contact pieces *E* made in the form of contact screws. These project in to the inside face of the insulating ring *D*. In order that these screws shall not wear the insulating ring *D* and become loose therein and that 65 they shall hold the insulating ring snugly against the inner face of the wall *a*, I form recesses in the interior of the insulating ring in which the nuts *F* are fitted, these nuts being screw threaded of course for the passage 70 of the contact screws *E*. A fiber sleeve *F'* or suitable fiber washers insulate the contact screws from the metallic wall *a*.

Exteriorly of the wall *a* and clamping against the same are the lock nuts *G* and 75 binding nuts *G'* which not only hold the screw *E* in position so that it shall not project more than required beyond the inner face of the insulating ring *D*, but also provide for the attachment of the usual electrical connections.

80 Mounted within the bearing *a'* is the rotatable spindle *H* which is adapted to be attached by the socket *H'* and set screw *H''* to a "half-time" shaft of the usual construction and operation. The upper end of the spindle *H* is provided with a transverse slot *I* in which is located a radially extending shiftable arm *J* which at its outer end carries a roller *K* preferably of steel. This 85 in most timers is adapted to contact with the inside face of the insulating ring *D* and to electrically connect with and move against the contact pieces inserted in the insulating ring *F*. My construction however provides 90 for a ring *L* preferably of steel, smaller than the inner circumference of the ring *D*, but large enough to surround the roller *K* and the upper end of the spindle *I*. This ring 95 is perfectly free to move and to be rotated 100 with a rolling contact against the interior face of the insulating ring *F* upon the rotation of the arm *J*. It is of course to be understood that the bottom of the ring is open and that the ring rests upon the bottom of 105 the casing *A*. The ring is of a height equal to the height of the insulating ring *F*, and contacts fully therewith when the roller *K* bears against it.

110 In detail the upper end of the spindle *H* is slotted from one point of its circumference to a diametrically opposite point,

and the arm J moves freely within this slot. The upper end of the spindle above the slot I is cut away as at i to permit the projection of a pin M which is fast 5 in the rear end of the arm J. A pin N projects from the end of the spindle and is fast thereto, and the pins M and N are connected by a spring O whereby the arm J is forced outward so that the roller K will be kept in 10 constant contact with the inner surface of the ring L and constantly acts to hold this ring tightly against the inner face of the insulating ring D.

The arm J is cut away on its underside 15 where it projects beyond the spindle H for the accommodation of the roller K. This roller is mounted upon a fixed shaft k having a head k' at one end and screwed at its other end into the projection j of the arm J.

20 In order that the ring L may move with perfect freedom, with as little friction as possible and may make a good contact with the contact pieces E, I provide means whereby a constant level of oil may be kept within 25 in the shell or casing A, and to this end I provide a bushing P which lines the interior face of the bearing a' and projects upward beyond the bottom of the casing A, thus forming in some sort a dam preventing the 30 outflow of the oil from the casing downward between the surface of the spindle H and the interior surface of the bearing.

As will be seen from Fig. 2, the upper 35 end of the spindle H where it projects into the casing A is diametrically enlarged, and the underside of this enlargement is formed with an annular recess h into which the upper end of the bushing P projects. Around this bushing the enlarged head of the spindle H rotates. This bushing I prefer to 40 make of phosphor bronze, pressed into the lower part of the shell and therefore having an oil tight joint therewith. By its retention of the oil it will reduce the wear of the 45 spindle H and the bearing to a minimum.

Q designates a bearing ring which is held upon the spindle H by the set screw H'', the upper face of the ring bearing against the lower edge of the casing A.

50 Electrical connections are to be made, as usual with this class of timers, from the contact pieces E to the usual induction coil, battery and sparking plug, a return circuit being made to the spindle H and through 55 the spindle H, arm J, roller K and the ring L to the contact pieces. As these connections are used in all timers of this character they have not been shown.

The operation of my invention is obvious. 60 As the spindle H rotates, the roller K will have a rolling contact with the interior face of the ring L, and this ring in turning will have a rolling contact with the interior face of the insulating ring F. As the ring L and 65 the roller K rotate, the ring will contact at

proper predetermined intervals with the contact screws or other pieces E to close the circuit and cause a spark to jump. It will be of course understood, that there may be as many contact pieces arranged around the 70 circumference of the timer as desired. I have shown two of these contact screws for a two cylinder engine, but of course the number used will correspond with the number of cylinders. 75

One of the main advantages of my invention lies in the fact that the interior surface of the ring F does not wear into ridges as is the case with timers of ordinary construction. This ridging of the interior face 80 of the insulating ring and of the segmental contacts usually used therewith makes the roller of the usual timer jump, thus preventing a good contact and causing the engine to miss fire. Another advantage incident to the use of the ring is that the points of the contact screws contact with the ring in a new place at each revolution, and thus the wear is evenly distributed around the 85 entire ring and does not come always in one place. A third advantage lies in the capability of adjusting the length of contact. If the screws E are turned inward the ring L will be retarded while the roller K is forced inward and passes over the projection. 90 During this time and until the roller has completely passed the projecting end of the contact screw, the ring is held. By turning the contact screws inward or outward, therefore it is possible to very accurately adjust 95 the length of contact between the ring and the contact screws. 100

While I believe that the construction here- 105 with shown is the preferable one, I do not wish to be limited thereto as it might be varied in many respects without departing from the spirit of my invention. Thus in place of contact screws, contact segments might be used, though these would not be as good as the contact screws. It is obvious 110 too that the ring F might be almost entirely composed of contact segments separated by small insulating pads as is sometimes used in timers of this construction. 115

As the cap B has an oil-tight engagement 115 with the casing A and as the bushing P projects up beyond the bottom of the casing, oil will be at all times retained within the casing and thus the ring, the roller and other parts connected therewith will be amply 120 lubricated.

While I have shown and described my timer as mounted with the casing horizontal and the spindle H vertical, I do not wish to be limited thereto as it could be used in any 125 position desired.

Having thus described my invention what I claim as new and desire to secure by Letters Patent is:

1. In an ignition timer, a circular casing 130

- having an annular wall and a central bearing, an insulating ring lining the wall of the casing, a cover closing said casing, contact pieces located in said insulating ring and 5 projecting through to the inside face thereof, a rotatable spindle mounted in the bearing of said casing and having a slotted upper end, an arm moving radially in said slotted end of the spindle, a contact roller carried 10 on its outer end, a spring mounted on the upper end of the spindle and engaging with said arm to move it radially outward, and a metallic conducting ring in said casing smaller than the same, surrounding the roller 15 and spindle and rotatable thereby against the inner face of the insulating ring and the contacts thereof.
2. In an ignition timer, a circular casing having an annular wall and a central bearing, an insulating ring lining the wall of the casing and having recesses on the outer face thereof, nuts in said recesses, contact screws 20 passing through said nuts and into the inner face of the insulating ring, and adapted to receive electrical connections leading to an engine cylinder, a metallic conducting ring in said casing smaller than the diameter of the insulating ring, a spindle located in said bearing and adapted to be placed in circuit 25 with the contact screws, said spindle having a metallic roller thereon adapted to contact with the inner face of the conducting ring.
3. In an ignition timer, a circular casing and a central tubular bearing, a phosphor 30 bronze bushing lining said bearing and rigid therewith and projecting into said casing.
- and a spindle rotatable within said bushing and casing, the end of said spindle being enlarged, said enlarged portion having a recess concentric to the axis of the spindle into 40 which the projecting end of said bushing shall extend.
4. In an ignition timer, a circular casing having an annular wall and a central tubular bearing, a cover for closing said casing, contact pieces located in said annular wall and projecting through the inside face thereof, a bushing mounted in said bearing and rigid therewith, said bushing projecting beyond the bottom of said casing, a rotatable spindle 50 mounted within said bushing and having an enlarged head provided with a circular slot concentric with the axis of the spindle and adapted to receive the projecting end of said bushing, an arm moving radially in guides 55 formed on the upper end of said spindle, a contact roller carried on the outer end of said arm, a spring mounted on the upper end of the spindle engaging with said arm to move it radially outward, and a metallic conducting ring in said casing smaller than the same surrounding the roller and spindle and rotatable thereby against the inner face of the insulating ring and the contacts thereof.

In testimony whereof I have signed my 65 name to this specification in the presence of two subscribing witnesses.

LORENZO B. SHIVERS.
